LINE SPACING MECHANISM FOR BUSINESS MACHINES

Lora Evans Tapp, Clarksville, Ind.; Lloyd E. Tapp, Loretta Sue Tapp, Larry Wayne Tapp and Lucille Marie Tapp, sole heirs of said Lora Evans Tapp, deceased

Application August 14, 1952, Serial No. 304,453

26 Claims. (Cl. 197—120)

(Granted under Title 35, U. S. Code (1952), sec. 266)

The invention described herein, if patented, may be manufactured and used by and for the Government for governmental purposes without the payment to me of any royalty thereon.

The present invention relates to line spacing mechanism for business machines and more particularly to an automatically operable line spacing mechanism for a motor driven business machine which is driven by the drive motor for the machine.

Conventionally the blank checks used in large commercial check-writing operations are made up in sheets each consisting of several checks arranged one after the other so that the individual checks may be successively positioned to be impressed by the machine by rotatably advancing the platen of the check writing machine. This is accomplished by pulling the line spacing lever conventionally provided on these machines through a pre-set stroke, each time the operation of filling out a check is completed. The manual manipulation of this lever not only becomes fatiguing during the course of a day's operation of the machine but also increases the possibility of error because the manual operation distracts the attention of the operator of the machine from the payroll or the like from which the operator is securing the names and amounts to be printed upon the succeeding check. This source of error and fatigue on conventional business machines such as check writers is eliminated by the improved devices of the present invention which is automatic in operation and operates mechanically to advance the platen of the machine at the proper time and in an amount sufficient properly to locate succeeding checks or the like in the machine.

Accordingly, an object of the invention is to provide a new and improved line spacer for business machines which operates automatically in timed relation to the operation of the machine to advance a blank or sheet in the machine the amount required properly to position the same for making successive impressions.

Another object of the invention is to provide a new and improved line spacer for a motor driven business machine which is automatically driven by the motor of the machine at a predetermined point in the cycle of the machine so that no manual effort is required to operate the same or to initiate operation thereof.

A further object of the invention is to provide a new and improved line spacer which may be installed upon conventional business machines with very little or no alteration thereof so that existing non-automatic machines may be readily converted to automatic operation.

A still further object of the invention is to provide a new and improved line spacer for business machines which does not disrupt the normal operation of the machine except for eliminating the need for manual line spacing so that no training is required to operate a machine equipped with this device and the machine may be operated as a conventional machine when desired.

Another object of the invention is to provide a new

2

and improved line spacer for business machines which is operated during the return stroke of the carriage of the machine so that no loss in operating time of the machine is occasioned by the use of the device.

Yet another object of the invention is to provide a new and improved line spacer for a business machine driven by the motor of the machine in which means is provided to insure operation of the device through a complete stroke.

10 A further object of the invention is to provide a new and improved line spacer for a business machine which is driven by the momentum of the drive motor of the machine.

A more general object of the invention is to provide a new and improved line spacer for a business machine which is relatively simple and sturdy in construction so that it is not subject to frequent breakdown and therefore is relatively inexpensive to construct, install and maintain.

20 These and other objects, advantages, and capabilities of the invention will become apparent from the following description wherein reference is had to the accompanying drawings in which:

Fig. 1 is a fragmentary side elevational view of a check writing machine showing the parts of the machine with which the line spacer directly cooperates and the position of these parts and the line spacer when the machine is inoperative;

Fig. 2 is a fragmentary sectional view taken on a vertical plane passing through the axis of the lever disclosed in Fig. 1;

Fig. 3 is a fragmentary side elevational view of a portion of the first embodiment of the improved line spacing mechanism of the present invention;

Fig. 4 is a fragmentary rear elevational view of the improved line spacing mechanism shown in Fig. 3 showing the parts in inoperative position;

Fig. 5 is a view partly in side elevation and partly in section along the line 5—5 of Fig. 4;

Fig. 6 is a fragmentary view of a part of the improved line spacing mechanism shown in Fig. 3 partly disassembled;

Fig. 7 is a view similar to Fig. 1 but showing a modification of the invention;

Fig. 8 is a fragmentary sectional view on a vertical plane passing through the axis of the lever of the modified line spacing mechanism disclosed in Fig. 7;

Fig. 9 is a rear elevational view of the modified line spacing mechanism with the parts thereof in inoperative position;

Fig. 10 is a fragmentary side elevational view of the modified line spacing mechanism showing its position relative to the drive motor of the business machine;

Fig. 11 is a vertical sectional view on the plane of the line 11—11 on Fig. 9;

Fig. 12 is a fragmentary view of a portion of the modified line spacing mechanism partly disassembled;

Fig. 13 is a vertical transverse sectional view of a portion of the one revolution clutch mechanism used in the modified line spacing mechanism; and

Fig. 14 is a fragmentary front elevational view of a control switch incorporated in the modified line spacing mechanism and the operating mechanism for this switch.

The present invention is continuation-in-part of my co-pending application for patent, Serial No. 89,542, filed April 25, 1949, and now abandoned, and entitled Automatic Spacer for Check Writing Machines.

Both embodiments of the line spacing mechanism disclosed in the present application are particularly adaptable for use on "Burroughs" check writing machines. The construction of these machines is well known and therefore will not be described in detail. Nevertheless it is

believed that a better understanding of the invention will be obtained by an illustration and brief description of the parts of a check writing machine with which the improved mechanism of the present invention directly cooperates. These parts are the same for both embodiments of the invention, and, therefore, they have been given the same numbers in all of the drawings.

Referring to Figs. 1 and 2 and to Figs. 7 and 8, portions of a "Burroughs" check writer upon which the line spacers of the present invention are particularly adapted for use are shown including a line spacing lever 10 having a spacing pawl 11 pivotally secured thereto which is adapted to engage the teeth of a line spacing gear 12 when the lever is swung counterclockwise as the parts are viewed in the figures mentioned. The line spacing gear 12 has teeth meshing with the teeth on a pinion 13 fixed on a shaft 14 which carries the platen or cylinder (not shown) by means of which a sheet of checks may be advanced in stages properly to locate the blank spaces thereon for receiving the impressions printed by the machine. The platen shaft 14 has hand knobs fixed on opposite ends thereof to permit manual rotation of the platen in a forward or rearward direction. One of these knobs is indicated in phantom at 15 in Figs. 1 and 7.

A carriage release lever 16 is also shown, together with a friction pawl engaging plate 18, a friction washer 19, and a shaft 20 upon which line spacing gear 12 rotates. Due to the driving connection established between line spacing gear and lever 12 and 10 respectively by the line spacing pawl 11, these parts rotate together when the lever is swung counterclockwise or operatively. However, upon return of the lever to cocked position it rotates on the hub of gear 12. In the embodiment of the invention shown in Fig. 1 to 6, lever 10 is returned to cocked position by a spring 17.

One end of the carriage of a check writing machine is indicated at 21, and the shaft 20 is fixed to this end of the carriage. A line space pawl eccentric 22 forms a fixed abutment against which the spacing pawl 11 engages when lever 10 is moved counterclockwise thus forming a stop to limit movement of the lever to a predetermined angle. This stop is adjustable to vary the stroke of lever 10 and thus to vary the amount a check is advanced during a cycle of the machine.

The line spacing devices of the present invention effect line-spacing motion of lever 10 by power derived from the electric drive motor for the machine. This motor is located below and on the rear side of the base of the machine. An electrically controlled clutch is interposed between the drive motor and the operating mechanism of the machine drivingly to connect the same for the interval required to drive the carriage of the machine through its forward or tabulating stroke. The motor and clutch are energized through separate running circuits.

Initial energization of this motor in a check writing operation is controlled by a motor control switch closed by operation of a conventional motor bar which is pressed once after the number and letter keys necessary to print the desired legend have been pressed. During the course of the return movement of the carriage after completion of that portion of the cycle of the machine during which the blanks in a check are filled out, the motor control switch is automatically tripped to discontinue energization of the motor, and the clutch is operated to disconnect the motor and the operating mechanism of the check writer. At substantially the same time the improved mechanism of the present invention automatically advances the platen far enough to bring the next check on the sheet in the machine to impressing position. Since the drive motor for the check writer, the motor bar, the number and letter keys, the motor control switch, the clutch and the normal operating circuits therefor are conventional in construction and operation, a detailed disclosure thereof is believed to be unnecessary.

This completes the description of the parts of a "Bur-

roughs" check writer believed to be necessary to an understanding of the invention, and the embodiment thereof shown in Figs. 1 to 6 will now be described. In Fig. 5 the shaft for the drive motor of the check writer is shown fragmentarily at 25. By means of a readily disengageable drive connection, shaft 25 is in permanent driving engagement with a stub shaft upon which a pinion 26 is splined which in turn drives a one revolution mechanism now to be described.

10 The stub shaft is rotatably mounted in ball bearings 27, 28 which are supported in a gear casing 29 and a gear casing cover plate 30 detachably secured by screws 31 (Fig. 4) to the casing 29. An inspection cap 32 is held by a spring 33 over the ball bearing 28 and may be swung to one side to permit oiling, etc. Drive pinion 26 drives a gear 34 (Figs. 5 and 6) which is loosely mounted on a cam shaft 35 journaled in ball bearings 36, 37 supported in the gear casing 29 and cover plate 30. An eccentric cam 38 is fixed on the cam shaft 35 by means of a collar 39 and a set screw 40 to lock the collar in position (Fig. 4). Fixedly mounted on a hub 34a on the gear 34 is a ratchet 41 (Figs. 5 and 6).

The one revolution clutch includes a plate 42 fixed upon shaft 35 and having a hub 42a abutting hub 34a and loosely received in the ratchet 41. A pawl 43 (Fig. 6) is pivoted on a pin 44 anchored in the plate 42, and a tension spring 45 reacting between the pawl 43 and a pin 46 anchored to the plate biases the pawl toward operative position. Pawl 43 has a notch or tooth 43a complementary to the teeth 41a in the periphery of the ratchet 41, and it also has a projecting cam edge 43b adapted to be engaged by a pin 47 to effect rocking of the pawl on its pivot in a direction to move the tooth 43a away from the ratchet. Pin 47 is slidably mounted in the gear casing 29 (Fig. 5) and is adapted to be reciprocated in an endwise direction into and out of the path of rotation of the cam edge 43b by operating mechanism controlled by movement of the carriage of the check writer, as will now be described.

Fixed to the backside of the carriage of the check writer is a rearwardly projecting trip comprising a roller 48 (Figs. 4 and 5) secured to and rotatable on a shaft 49 adjustably mounted on the carriage. Roller 48 is adapted to contact and pass over a trip pawl 50 when the carriage tabulates (i. e., moves from left to right as seen in Fig. 4) because this pawl is pivoted as at 50a on a bell crank lever 51. The bell crank lever is swingable on a pivot 52 supported on a strap 53 secured to a fixed part of frame of the machine and is biased in a clockwise direction (Fig. 4) by a tension spring 54. A smaller spring 55 biases trip pawl 50 into abutting engagement with a fixed spring post 54a. Springs 54 and 55 extend in opposite directions and are both connected to spring post 54a which projects from bell crank lever 51 and serves as a stop, to limit swinging of the trip pawl under the influence of spring 55.

55 On return movement of the carriage (i. e., from right to left in Fig. 4) the trip pawl 50 is struck by roller 48, and since it is locked against counterclockwise rotation by spring post 54a the force of the impact is transmitted to the bell crank 51 and rocks the latter counterclockwise. 60 A link rod 56 couples the free end of the bell crank lever 51 to one arm of a second bell crank lever 57 (Fig. 5) pivoted on a stud 58. The second arm of bell crank lever 57 projects upwardly through a slotted externally projecting end of the reciprocable pin 47 which pin is slideable in a guide 59 on the gear casing 29. Downward movement imparted to the link rod 56, when the bell crank 51 is rocked by impact of the roller 48 on trip pawl 50 during the return of the carriage swings bell crank lever 51 in a counterclockwise direction (Fig. 5). This causes the slideable latch pin 47 to be withdrawn from contact with cam surface 43b on the pawl 43 so that the biasing force of the spring 45 becomes effective to rock the pawl in a direction to engage tooth 43a upon one of the ratchet teeth 41a. A driving connection 65 is thus established between the plate 42 on the one hand

and the motor driven gear 34 on the other through the ratchet 41 which is fixed upon the hub of gear 34.

Rotation of the plate 42 is limited to a single turn because the slidable pin 47 moves into the orbit of the cam surface 43b as soon as the roller 48 moves far enough to the left (Fig. 4) to release trip pawl 50 which occurs almost instantaneously and with a snap action due to the biasing force of spring 54. As the rotating parts complete one turn the slidable pin 47 is engaged by the camming surface 43b on pawl 43 thus rocking the latter on its axis 44 in a direction to release the ratchet 41 and associated parts. Thus the cam shaft 35 is rotated through a single turn (360°) during each return stroke of the carriage. Tensioning of the pawl spring 45 by the camming action of pin 47 on the pawl 43 has a braking effect and prevents undesirable jarring of the mechanism when rotation of camshaft 35 and the parts secured thereon is thus abruptly arrested.

In view of the fact that eccentric cam 38 is fixed on the shaft 35 driven by rotation of the plate 42 in the manner above described, it will be rotated counterclockwise (Fig. 4) through one complete turn during each cycle of the one revolution mechanism above described. Cam 38 engages a cam follower roll 60 rotatably mounted on a cam follower arm 61 which is pivoted at one end upon an eccentric mounting 63 carried by the gear casing cover plate 30. By turning this mounting the position of the roller 60 relative to axis of the cam 38 may be varied so as to vary the amount the roller 60 is displaced during each turn of cam 38 and thus vary the stroke of the cam follower arm 61.

A tension spring 64 is attached at one end to the cam follower arm 61 and is anchored at its other end by means of a screw 65 to the cover plate 30, so as to bias the arm 61 in a direction constantly to maintain the cam follower roller 60 in contact with the cam 38. A cable 66 is secured at one end by a screw 67 and clip 68 to the free end of the cam follower arm 61, and is slidable through a flexible housing 69, the housing and cable both extending upwardly to an operative connection with the line spacing lever 10 now to be described.

Referring again to Fig. 1, the upper end of cable housing 69 is anchored to the carriage of the check writer by means of a clamp 70, a clamping screw 71, and a clip 72. A portion of the cable 66 external to the upper end of casing 69 is wrapped part way around a cable drum 73 having a grooved periphery to receive the cable as shown in Fig. 2. Cable drum 73 is rotatably supported on the shaft 20 fixed in the right end of the carriage 21. A coil spring 74 which is secured at one end to the cable drum 73, extends partly around its grooved periphery and is anchored at its opposite end to any suitable fixed connection such as the cable housing as indicated at 75 so as to place the coil spring 74 under constant tension. The spring 74 thus biases the cable drum 73 for clockwise rotation (Fig. 1), i. e., in a direction to wind cable 66 thereon and thus maintain the latter taut at all times so that any movement of the cam follower arm 61 by the cam 38 will immediately be imparted to the cable drum 73 and will tend to rotate the same counterclockwise.

Cable drum 73 has a pin 76 fixed in and projecting axially outwardly from the side of the drum facing the line spacing lever 10 at a position to engage the rear edge thereof when the cable drum is rotated counterclockwise and thus to rotate the line spacing lever in the same direction. Upon initial rotation of the line spacing lever 10 either by operation of the cable drum 73 or by manual operation of the lever the friction pawl engaging plate 18 which is operatively connected to the line spacing pawl 11 and engages loosely over fixed shaft 20, lags due to contact with the stationary friction pawl engaging washer 19 causing pawl 11 to be rocked in a direction to engage one of the teeth on the line spacing gear 12. Continued counterclockwise rocking of the lever 10 there-

after either manually or by virtue of the pull exerted by cable 66 on cable drum 73 drives the line spacing gear 12 in the same direction and through pinion 13 engaged therewith rotates the shaft 14 and the platen fixed thereon through one line spacing step or stage. Since the pin 76 is located on the trailing side of the line spacing lever 10, it does not interfere with manual operation of the lever if that is desired.

From the foregoing description of the improved attachment of the present invention, its operation should be clear, but may be summarized as follows: Assuming that the sheet of checks has been inserted in a check writing machine equipped with the attachment, the operator, by means of hand knobs 15, rotates the platen to bring the first check into the proper position to be impressed, presses the proper number and letter keys and then touches the motor bar. Immediately the machine will automatically type the amount on the check, register the total, and return the carriage to its original or "home" position. During the return stroke of the carriage, the roller 48 carried thereby engages the right hand side (Fig. 4) of the trip pawl 50, and since this pawl is locked against counterclockwise rotation by spring post 54a anchored to bell crank 51, the latter will be rocked counterclockwise on pivot 52 as the carriage continues its return movement. This forces link 56 downwardly rocking bell crank 57 counterclockwise (Fig. 5) upon its axis 58 so that latch pin 47 is retracted outwardly relative to the casing 29 thus releasing pawl 43 whereupon pawl 43 is rocked counterclockwise (Fig. 6) to operative position by spring 45 and one of the teeth on ratchet wheel 41 engages the tooth 43a on the pawl.

Since ratchet wheel 41 is being rotated counterclockwise (Fig. 6) during return of the carriage (through gear 34 to which it is fixed and pinion 26 which has a direct driving connection to the motor shaft 25 shown in Fig. 5) the pawl carrying plate 42 will be rotated in the same direction, and since the shaft 35 is fixed to this plate, this shaft will be rotated in a like direction. The cam 38 (Fig. 4) is thus rotated in a counterclockwise direction rocking lever 61 from the full line position shown in Fig. 4 to the dotted line position. An endwise pull is thus exerted on flexible cable 66 sufficient to rotate the disk-shaped drum 73 (Fig. 1) in a counterclockwise direction against the resistance of the return spring 74. As the drum rotates pin 76 fixed thereon is carried into engagement with operating lever 10 and rocks the latter counterclockwise. Initial movement of the lever in this direction effects engagement of the teeth on pawl 11 with the teeth on line spacing gear 12 so that this gear is rocked in the same direction for a distance determined by the adjustment of stop 22. The platen is thus advanced the amount determined by this adjustment.

It should be noted that the roller 48 is located at such a position on the carriage that the bell crank 51 and the mechanism operated thereby are actuated substantially at the time the control switch for the motor of the machine automatically discontinues operation of the motor. However, the momentum of the motor carries the return and line spacing mechanism through their complete cycle or stroke.

Inasmuch as the latch pin 47 is held in retracted position only during the return passage of the roller 48 over trip pawl 50 the latch pin returns to operative position with a snap action very shortly after it has been retracted and thus as the plate 42 and pawl 43 approach completion of one revolution, pawl 43 engages pin 47 and is cammed thereby to retracted position as indicated in Fig. 6. This breaks the driving connection between motor driven gear 34 on the one hand and the pawl plate 42 and shaft 35 on the other so that the drive to cam 38 is discontinued. Cam 38 is so arranged that its high point has passed the follower 60 when the drive to the same is discontinued and thus the line spacing mechanism including the handle 10, line spacing gear 12 and drum

73 may be returned to inoperative position by the return spring 74.

The embodiment of the invention disclosed in Figs. 7 to 14 for automatically operating the line spacing lever 10 through a stroke each time the printing mechanism in the check writer completes filling in a check so as automatically to position the succeeding check on a sheet of checks to be filled out includes one revolution driving mechanism supported by a casing 80 (Figs. 10 to 12) closed by a removable cover plate 81. This casing has a recess 82 (Fig. 10) to receive the central boss on the rear end bell 83 of the driving motor for the check writer and may be fixedly secured thereto by means of cap screws, etc., (not shown). Projecting from the end bell 83 is a motor shaft fragmentarily shown at 84 which shaft is in permanent but readily disconnectable engagement with a stub shaft 85 so that the latter rotates in unison with the motor shaft 84.

The one revolution clutch mechanism comprises reduction gearing including a pinion 86 on the stub shaft 85 (Figs. 11 and 12), and a gear 87 driven by the pinion 86 and fixed upon an intermediate shaft 88 which also has a pinion 89 fixed thereon and engaged with a gear 90. The latter gear and a ratchet 91 are co-axially fixedly interconnected as by mounting the ratchet on a bearing sleeve or bushing 92 press-fitted into the gear 90 and welding or brazing the parts together. These parts are rotatably supported upon a crank shaft 93 which also has a disk-shaped carrier plate 94 fixed thereon.

Stub shaft 85 is rotatably supported in a shouldered bearing sleeve or bushing 95 fixed in the portion of the casing which is recessed so as to hold the stub shaft 85 in co-axial alignment with the motor shaft 84 when the casing 80 is fixed in position while the shafts 88 and 93 may be rotatably supported in suitable anti-friction bearings 96 supported in the casing 80 and cover plate 81. It is to be observed that by reason of this gearing the ratchet 91 will be driven at a greatly reduced velocity compared to the velocity of motor shaft 84 and in a clockwise direction as viewed in Fig. 13.

A positive driving connection is established between the crank shaft 93 and ratchet 91 through the carrier disk 94 by means of a pawl 97 (Fig. 13) rockably supported upon a pin 98 anchored in the carrier disk 94. This pawl has a tooth 99 confronting the teeth 100 on ratchet 91, and it is biased by a tensioned spring 101 for rocking movement in a direction to bring the tooth 99 into engagement with one of the teeth on the ratchet.

During such engagement clockwise rotary movement of the ratchet as seen in Fig. 13 is transmitted to carrier disk 94 and crank shaft 93 so that both of these parts are positively driven in the same direction. At a predetermined point in the rotation of carrier disk 94 a notch or tooth 102 in the outer peripheral edge of the pawl 97 hooks against the edge of a latch pin 103 pivotally secured in the casing 80 provided the pin is turned to a position at which a recess 104 in the pin is at least partially turned away from the path of rotation or orbit of the tooth 102 on the pawl 97 as shown in full lines in Fig. 13. Thereupon an angular force in opposition to the force exerted by spring 101, and of larger magnitude in view of the fact that it is derived from the drive motor, is exerted on the pawl 97 causing the same to rock until the ratchet 91 is released by the tooth 99. The ratchet 91 is then free to rotate independently of the carrier disk 94 and crank shaft 93 and the latter two parts are locked against rotation.

The recess 104 in latch pin 103 is of sufficient depth so that tooth 102 on pawl 97 will be released at a point in the pivotal movement of the pin at which the recess is brought to a position squarely facing pawl 97 as shown in dotted lines in Fig. 13. The pawl 97 will then be rocked clockwise by the spring 101 until inwardly facing tooth 99 thereon engages one of the teeth 100 on ratchet 91. A positive driving connection between the ratchet 91 and

the carrier disk 94 and crankshaft 93 is thus established as previously explained.

Latch pin 103 is turned in timed relation to the cycle of operation of the check writing machine by mechanism 5 similar to that described for performing an analogous function on the latch pin used in the first embodiment of the invention. Referring to Figs. 9 and 11 a trip roller 48 is there shown mounted on shaft 49. This shaft is fixed in the back of the carriage of the check writer so as 10 to be carried back and forth by the carriage when the check writer is in operation. On the forward or tabulating stroke of the carriage, i. e., from left to right as seen in Fig. 9, the trip roller 48 is carried to the right of a rockable member including a bell crank lever 105 (Fig. 15) pivoted at its intermediate part upon a pin 106 carried by an arm 107 fixed to the frame of the machine.

One arm of this bell crank projects generally horizontally, while the other projects generally vertically and has a nose 108 rockably mounted on a pin 109 fixed in 20 the bell crank. The nose 108 is biased by a spring 110 in a direction to bring the base thereof into abutting engagement with a fixed post 111 on the bell crank. By reason of this construction the nose 108 is free to rock in a clockwise direction as seen in Fig. 9 as when it is 25 struck by the roller 48 during the course of the forward motion of the carriage. However, the nose is locked against counterclockwise movement so that the impact of the roller 48 on the nose during the return stroke of the carriage (i. e., during its movement from right to 30 left) is imparted to the bell crank 105.

This force is sufficient to rock the bell crank counterclockwise (Fig. 9) and to depress a connecting link 112 having one of its ends secured to the horizontal arm of the bell crank and its other end connected to a rocker 35 arm 113 at a point spaced from the point at which this arm is fixed to a part of the latch pin 103 projecting from the casing 80.

As a result the arm 113 and latch pin 103 are rocked clockwise (Fig. 13) bringing the recessed end of pin 103 40 into the orbit of the tooth 102 on the pawl 97 so that the latter is released and a driving connection is established between the crank shaft 93 and gear driven ratchet 91 in the manner previously described.

However, the latch pin 103 is turned to this position 45 only momentarily because the roller 48 quickly passes far enough to the left (Fig. 9) to release nose 108. The latch pin 103, rocker arm 113, link 112 and bell crank 105 are then restored to the position shown in Figs. 9 and 13 by a tensioned spring 114 fixed at opposite ends 50 to the casing 80 and the arm 113 and passing over the portion of the end bell 83 for the motor shown in Fig. 10. As a result when the ratchet 91 and carrier disk 94 complete one turn, the latch pin 103 will again be in a 55 position to hook against tooth 102 on the pawl 97 and thus release the driving connection between the gear driven ratchet 91 on the one hand and the carrier disk 94 and crank shaft 93 on the other. Thus the crank shaft 93 makes only one turn in each cycle of operation of the check writing machine.

Fixed upon a portion of the crank shaft 93 projecting through the cover plate 81 is a crank arm 115 connected by a pitman 116 to a connecting rod 117, having a head 118 to which the pitman 116 is connected and a rigid extension 119. Crank arm 115 and carrier disk 94 are so 60 positioned on crank shaft 93 that the crank arm 115 is in the vertical position shown in Fig. 9 when rotation of the crank shaft 93 is arrested in the manner previously described. The head 118 is guided for reciprocatory movement by a fin 120 projecting from the same into a 65 slideway 121 fixed on the outer side of the cover plate 81, while the rigid extension 119 is reciprocable in a rigid tubular guide member 122 anchored in a clamping block 123 fixed to the outer side of the cover plate 81 adjacent its upper end.

The rigid extension 119 on the connecting rod is fixed

to one end of a flexible cable or shaft 124 freely reciprocal in flexible housing 125 anchored at one end to the free end of the rigid tubular guide member 122 and at its other end to a boss 126 (Fig. 7) on a drum race 127 secured by screws to the end 21 of the carriage of the check writer. A cable drum 128 is loosely received in this race and fits loosely over the hub of line spacing lever 10 (Fig. 8). A portion of the flexible cable 124 extending from the housing 125 is wound upon a portion of the grooved periphery of the cable drum 128 (Fig. 8) and is anchored to a block 129 fixed on the cable drum 128. By virtue of this construction a pull such as will be imparted to the cable 124 through the crank shaft 93, pitman 116 and connecting rod 117 during each cycle of the crank shaft will rotate the cable drum 128 in a counterclockwise direction (Fig. 7) an amount determined by the length of the pull. This, of course, is controlled at least in part by the length of the crank arm 115.

Projecting outwardly from the inwardly facing side of the cable drum 128 is a drive pin 130 which engages the trailing side of the line spacing lever 10 when the drum is rotated by a pull on cable 124 thus rocking the lever 10 counterclockwise (Fig. 7) through an operating stroke during the course of a cycle of the crank shaft 93 and crank arm 115 and advancing the line spacing gear 12 and platen in a manner previously described. Return of the line spacing lever 10 to inoperative position is assured by a torsion spring 131 housed in an annular recess 132 in the cable drum 128 and anchored at opposite ends to the drum and the lever 10 so as to exert a constant force on this lever in a return direction.

In check writers of the type previously mentioned, an automatically operable switch de-energizes the driving motor of the check writer upon completion of each individual check writing operation and electrically controlled clutches are provided automatically to disconnect the motor shaft from the parts of the check writer driven thereby at this time as previously mentioned. In conventional machines the clutch remains inoperative until the motor bar is again operated. Although momentum may continue operation of the motor momentarily after it is disengaged from the operating mechanism of the check writer and thus begin the cycle of operation of the line spacing or check advancing mechanism, it will not continue operation of this mechanism long enough to advance a check through a complete cycle in view of the relatively large reduction between the pinion 86 and crank shaft 93.

A "Micro-Switch" 133 of conventional construction (Fig. 14) is therefore provided on the casing 80 through which the motor of the check writer may be energized independently of the conventional running or energizing circuits and switches controlled by the conventional motor bar. This Micro-Switch controls a circuit which is parallel to the conventional circuits above mentioned and through which the motor may therefore be energized independently of these conventional energizing or running circuits. Switch 133 is controlled by a cam 134 fixed upon the end of crank shaft 93 projecting from the casing 80 opposite that on which the crank arm 115 is secured. This cam has a short dwell so that momentum of the operating motor of the check writer drives the crank shaft 93 far enough to close the Micro-Switch 133. The operating motor of the check writer therefore will continue to run until the crank shaft 93 and the cam 134 fixed thereon have been driven through one turn whereupon the contacts of the Micro-Switch will be opened by virtue of the change of position of cam 134. Thereafter, the operating motor for the check writer will remain idle until the motor-bar is again pressed. Operation of the check or platen advancing mechanism through a complete stroke is thereby assured.

From the description of the construction of this second embodiment of the invention and the description of the

operation of the first embodiment the operation of the second embodiment will be clearly understood without further explanation. From this description, it will also be apparent that the improved check advancing mechanism of the present invention does not interfere with manual operation of a check writer in a conventional manner. Moreover, the devices of the present invention may be readily installed as an accessory on existing machines because very little modification of these machines is necessary to adapt the same for operation with the line spacing or check advancing means of the present invention. This not only reduces the cost of modifying existing machines but also makes possible the construction of check writers with these line spacers as original equipment at very little added cost.

A further advantage of the invention is the fact that both embodiments thereof are positively operated at least through the portion of the cycle when a check is being advanced, and in the second embodiment this mechanism is also driven positively on its return stroke. Moreover, the second embodiment of the invention is positively driven by the motor of the check writer upon which it is used throughout its cycle of operation because of the auxiliary motor energizing circuit provided with that form of the invention.

Elimination of fatigue in the use of check writing machines by the elimination of manual line spacing is only one of the advantages derived from the present invention. In addition, the accuracy and speed of an operator are increased because the operator's attention is not distracted by looking for or reaching for a hand lever to advance a check.

While preferred embodiments of the invention have been shown and described, it will be apparent that numerous variations and modifications thereof may be made without departing from the underlying principles of the invention. It is desired, therefore, by the following claims, to include within the scope of the invention, all such variations and modifications by which substantially the results of the invention may be obtained through the use of substantially the same or equivalent means.

What I claim is:

1. In combination with a motor-driven check writing machine having a reciprocable carriage adapted to carry a sheet of checks and having a line spacing lever, said motor having a shaft, an automatic line spacing mechanism comprising a roller fixed to the carriage, means constructed and arranged to be operated by said roller at one point only in the carriage cycle, a single-revolution clutch operated by said means to be engaged with the motor shaft, a camshaft engaged with the motor shaft by said clutch so as to be rotated a single revolution at a time, a cam on the camshaft, a cam follower moved by the cam, a cable pulled by the cam follower when so moved, and mechanism operated by the cable to move the line spacing lever to effect line spacing.

2. A check writing machine as defined in claim 1, wherein the mechanism which is operated by the cable includes a cable drum about which the cable is partly wound, a stud fixed to and projecting from the cable drum at a position to contact the line spacing lever for swinging the latter to effect line spacing, and a tension spring secured to the cable drum and opposing the pull of the cable.

3. In combination with a power source, a carriage which may be shifted back and forth, a line spacing mechanism on the carriage, a flexible cable for operating the line spacing mechanism, a cam follower arm to which the cable is secured, a rotary camshaft, a cam fixed to the camshaft and adapted when rotated to swing the cam follower arm to pull the cable, a clutch interposed between the power source and the camshaft, and a carriage-tripped mechanism operable only at a certain point in the cycle of the carriage to move parts of the clutch to effect power drive of the camshaft through a

11

single revolution and hence operation of the line spacing mechanism through a single cycle.

4. In combination with a motor-driven check writing machine having a shiftable carriage for carrying a sheet of checks and a manually operable line spacing lever with a tension spring to return the lever to normal position, an automatic line spacing mechanism comprising a member adapted directly to engage said lever to move it in a direction to effect line spacing, a cable drum carrying said member, a cable attached to and wound part way around the drum, a spring connected to the drum and imposing a constant tension on the cable, a trip on the carriage, and a mechanism including a single revolution clutch coupled with the motor when actuated by the carriage trip to impart a single pull to the cable against the tension of the second mentioned spring, the pull occurring once during each cycle of the carriage.

5. An attachment for an electric motor-driven check writing machine having a reciprocable carriage, a swingable line spacing lever on the carriage and a spring for returning the line spacing lever to normal position; said attachment including a stud adapted to contact the line spacing lever directly to swing it in a line spacing direction; means including a cable connected to operate the stud; a pinion constantly driven by the motor shaft; a gear driven by the pinion; a ratchet secured to and rotating with the gear; a plate; a pawl pivoted on the plate and adapted to engage the ratchet; a spring tending to engage the pawl with the ratchet; a shaft supporting the gear, ratchet and plate and fixed to the plate; a pin slidable into and out of engagement with the pawl and disengaging the pawl from the ratchet by a cam action; a cam fixed to said shaft; a cam follower arm moved by said cam; means connecting the cam follower arm with said cable; a trip fixed upon the carriage; and mechanism actuated by the trip to move said pin out of contact with the pawl so that the pawl will automatically engage the ratchet to couple the plate, pawl, ratchet and gear together thereby to rotate the shaft and hence the cam through a single revolution.

6. The invention defined in claim 5, wherein the means to operate the stud comprises a cable drum rotatably supported coaxially with the line spacing lever, one end of said cable being wrapped partly around said drum; the spring for returning the line spacing lever to normal position being a tension coil spring anchored at one end and partly wrapped about said drum in an opposite direction to the direction of wrapping of said cable and secured to said drum so that said cable is normally under tension from said spring; said stud being fixed to the cable drum and projecting therefrom and adapted to contact the line spacing lever at a point spaced from its axis to swing said lever to effect line spacing.

7. In a motor driven business machine having a reciprocable carriage supporting a platen for rotation relative thereto, the combination comprising one-way driving mechanism to rotate said platen through a predetermined angle during each cycle of the driving mechanism, means including a flexible cable to drive said one-way driving mechanism, a shaft having a driving connection with the motor of said machine, means for applying force in an endwise direction to said cable to actuate said one-way driving mechanism, clutch mechanism operatively to connect said shaft and the force applying means to operate the latter, means to latch said clutch mechanism in inoperative position, latch tripping means, and means to render said latch tripping means operative to trip the latch means during the return stroke of said carriage.

8. In a motor driven business machine having a rotatable platen carried by a carriage reciprocable relative to the frame of the machine, the combination comprising ratchet and pawl mechanism for rotatably advancing said platen through a predetermined angle in each cycle of said ratchet and pawl mechanism, means including a handle manually operable at will to actuate said ratchet

12

and pawl mechanism through said predetermined cycle, and means automatically to actuate said ratchet and pawl mechanism through said predetermined cycle during return movement of said carriage including a rockable lever, 5 clutch mechanism for operatively connecting said lever and motor to render the latter effective to rock the lever including elements biased for relative movement to one position, a latch to lock said elements against relative movement to said position and cooperating latch tripping mechanism including elements on said frame and an element reciprocable in a forward and return direction with said carriage, one of said frame elements being yieldable on forward movement of said carriage so that said mechanism is operative only on return movement 15 of the carriage, and a drive connection between said lever and said ratchet and pawl mechanism for actuating the latter to advance said platen through said predetermined angle in response to each cycle of movement of said rockable lever.

20 9. In a motor driven business machine having a rotatable platen carried by a carriage reciprocable relative to the frame of the machine, the combination comprising ratchet and pawl mechanism for rotatably advancing said platen through a predetermined angle in each cycle 25 of the said mechanism, and means automatically to actuate said ratchet and pawl mechanism through said predetermined cycle during return movement of said carriage including a rockable lever, clutch mechanism for operatively connecting said lever and motor to render the latter effective to rock the lever including elements biased for relative movement to one position, a latch to lock said elements against relative movement to said position and cooperating latch tripping mechanism including elements on said frame and an element reciprocable in a 30 forward and return direction with said carriage, one of said frame elements being yieldable on forward movement of the carriage so that said mechanism is operative only on return movement of the carriage and a drive connection between said lever and said ratchet and pawl mechanism for actuating the latter to advance said platen through said predetermined angle in response to each cycle of movement of said rockable lever.

40 10. In a business machine having a rotatable platen carried by a carriage reciprocable relative to the frame of the machine, the combination comprising ratchet and pawl mechanism for rotatably advancing said platen through a predetermined angle in each cycle of said mechanism, a handle manually operable at will to actuate said ratchet and pawl mechanism through said predetermined cycle, and other mechanism automatically to actuate said ratchet and pawl mechanism through said predetermined cycle during return movement of said carriage including a generally disk-shaped element pivotally rockable relative to said handle, a part on said disk-shaped element to engage said handle when the disk-shaped element is rocked on its axis for rocking the handle in a direction to actuate said ratchet and pawl mechanism to advance said platen, a rockable lever, a driving connection between said lever and disk-shaped element for actuating the latter to advance said platen when the lever is rocked in one direction, and means to rock said lever through one cycle during each return movement of said carriage.

45 11. In a business machine having a rotatable platen carried by a carriage reciprocable relative to the frame of the machine, the combination comprising ratchet and pawl mechanism for rotatably advancing said platen through a predetermined angle in each cycle of the said mechanism, a handle manually operable at will to actuate said ratchet and pawl mechanism through said predetermined cycle, and other mechanism automatically to actuate said ratchet and pawl mechanism through said predetermined cycle during return movement of said carriage including a drum rotatable relative to said handle, a fixed abutment on said drum to engage said handle when the drum is rotated 50 for rocking the handle in a direction to actuate said ratchet

and pawl mechanism for advancing said platen, a rockable lever, a flexible drive cable wound adjacent one end upon said drum so that a force in one direction on the cable causes the drum to rotate in a direction to bring said abutment into driving engagement with said handle, the other end of said cable being fixed to said lever so that a force is exerted on the cable in a direction to rotate the drum when the lever is rocked in one direction, and means to rock said lever through one cycle during each return movement of said carriage.

12. In a business machine having a reciprocable carriage supporting a platen for rotary movement relative thereto, the combination comprising ratchet and pawl mechanism for rotatably advancing said platen in predetermined increments including a handle manually pivotally rockable to effect forward pivotal movement of said platen, a drum co-axially arranged with respect to said handle and pivotally rockable independently thereof, driving mechanism adapted to be driven through a predetermined stroke in response to predetermined movement of said carriage, a flexible cable drive operatively connected to be pulled by said driving mechanism during the cycle of the latter and to be at least partially wound on said drum so that the latter will be rotated through a predetermined angle in an unreeling direction when the flexible cable is pulled by the driving mechanism, and a fixed abutment on one of said pivotally rockable parts to establish a driving connection between the handle and drum when the drum is rocked by a pull on the cable.

13. In a motor driven business machine having a reciprocable carriage supporting a platen for rotation relative thereto, the combination comprising step-by-step drive means rotatably to advance said platen in predetermined increments including a pivotally rockable driving member, a flexible drive shaft having a portion of its length wound on said driving member so that a pull on the drive shaft pivotally rocks said rockable driving member, a rockable lever, means for operatively connecting the flexible shaft and lever to render the latter operative when rocked to exert a pull on the shaft, means to rock said lever, and means automatically rendered operative at a predetermined point in each cycle of movement of said carriage to drive said lever rocking means sufficiently to rock said lever through a complete stroke.

14. In a motor driven business machine having a reciprocable carriage supporting a platen for rotation relative thereto, the combination comprising step-by-step drive means rotatably to advance said platen in predetermined increments, mechanism to actuate said step-by-step drive means including a rotatable shaft, means automatically operable in response to reciprocatory movement of the carriage to rotate said shaft a predetermined amount during a predetermined portion of each cycle of the carriage, a crank driven through one complete stroke during each cycle of the shaft, and a driving connection between said crank and said step-by-step drive means to advance the latter a predetermined amount during each revolution of the crank.

15. In a motor driven business machine having a reciprocable carriage supporting a platen for rotation relative thereto, the combination comprising step-by-step drive means rotatably to advance said platen in predetermined increments including a pivotally rockable driving member, a flexible drive shaft having a portion of its length wound on said driving member so that a pull on the drive shaft pivotally rocks said rockable driving member, mechanism to actuate said step-by-step means including a rotatable shaft, means automatically operable in response to reciprocatory movement of the carriage to rotate said shaft a predetermined amount during a predetermined portion of each cycle of the carriage, and a crank driven through one complete stroke during each cycle of the shaft, said flexible drive shaft

being operatively connected to said crank so that a pull is exerted on the said shaft during half the cycle of the crank.

16. In a motor driven business machine having a carriage reciprocable through a predetermined stroke and supporting a platen for rotation relative thereto and a tripping member for reciprocatory movement therewith, the combination comprising drive means rotatably to advance said platen in predetermined increments, mechanism to actuate said drive means including a clutch operatively to connect the drive motor for said machine and said drive means and automatically to discontinue operation of the drive means upon predetermined operation of the latter, an articulated lever pivotally secured upon a fixed axis and having a terminal portion disposed in the path of movement of the tripping member on said carriage and yieldable selectively to resist passage of the said member so as to render said tripping member effective to rock the lever as a unit at a predetermined point in the cycle of the carriage, and a drive connection between said articulated lever and clutch to render the latter operative when the lever is rocked as a unit.

17. In a motor driven business machine having a carriage reciprocable through a predetermined stroke and supporting a platen for rotation relative thereto and a tripping member for reciprocatory movement therewith, the combination comprising drive means rotatably to advance said platen in predetermined increments, mechanism to actuate said drive means including a clutch operatively to connect and disconnect the drive motor for said machine and said drive means, an articulated lever pivotally secured upon a fixed axis and having a terminal portion disposed in the path of movement of the tripping member on said carriage and yieldable selectively to resist passage of the member so as to render said tripping member effective to rock the lever as a unit at a predetermined point in the cycle of said carriage, a drive connection between said articulated lever and clutch to render the latter operative when the lever is rocked as a unit, means abruptly and automatically to disengage the clutch and discontinue operation of the drive means upon predetermined operation of the latter, and means to cock said last-mentioned means and lever with a snap action.

18. In a motor driven business machine having a reciprocable carriage supporting a platen for rotation relative thereto, the combination comprising platen driving means rotatably to advance said platen including driving and driven clutch members having cooperating parts relatively movable between predetermined relative positions drivingly to connect or disconnect said clutch members, a radial projection on the driven member, means to bias the cooperating parts of said clutch members to one relative position, a relatively elongated latch member having a part movable into and out of the orbit of said projection for arresting rotary movement of said driven member and to effect movement of said cooperating parts to one relative position under the influence of the momentum of the arrested member, an articulated drive connection positively to move said latch member, and means including a member on said carriage to actuate the articulated drive connection at a predetermined point in the movement of said carriage for effecting withdrawal of the latch member from the orbit of said driven member so that the latter and the cooperating parts are freed for movement.

19. In a motor driven business machine having a reciprocable carriage supporting a platen for rotation relative thereto, the combination comprising platen driving means rotatably to advance said platen including driving and driven clutch members having cooperating parts relatively movable between predetermined relative positions drivingly to connect or disconnect said clutch members, a radial projection on the driven member, means to bias the cooperating parts of said clutch members to one relative position, a relatively elongated latch member hav-

ing a part movable into and out of the orbit of said projection for arresting rotary movement of said driven member and to effect movement of said cooperating parts to one relative position under the influence of the momentum of the arrested member, an articulated drive connection positively to move said latch member, and means including a member on said carriage to actuate said articulated drive connection through a complete stroke with a snap action at a predetermined point in the movement of said carriage for thereby effecting withdrawal of the latch member from the orbit of said driven member for an interval of time less than the clutch members require to complete one revolution and so that said clutch members are freed for relative movement to their other predetermined position for said interval.

20. In a motor driven business machine having a reciprocable carriage supporting a platen for rotation relative thereto, the combination comprising platen driving means rotatably to advance said platen including driving and driven clutch members having cooperating parts relatively movable between predetermined relative positions drivingly to connect or disconnect said clutch members, a radial projection on the driven member, means to bias the cooperating parts of said clutch members to one relative position, a relatively elongated latch pin having a part reciprocable in an endwise direction into and out of the orbit of said projection for arresting rotary movement of the driven member, and articulated latch pin retracting means including a trip rendered operative in response to predetermined movement of the carriage to actuate said latch pin retracting means.

21. In a motor driven business machine having a reciprocable carriage supporting a platen for rotation relative thereto, the combination comprising platen driving means rotatably to advance said platen including driving and driven clutch members having cooperating parts relatively movable between predetermined relative positions drivingly to connect or disconnect said clutch members, a radial projection on the driven member, means to bias the cooperating parts of said clutch members to one relative position, a latch including a part pivotally rockable to and from a position obstructing the orbit of said projection to adapt said latch for arresting said driven member, a rocker connected pivotally to rock said latch, and means pivotally to rock said rocker in timed relation to the movement of said carriage to a position at which said latch is shifted to driven member arresting position.

22. In a motor driven business machine having a reciprocable carriage supporting a platen for rotation relative thereto, the combination comprising platen driving means rotatably to advance said platen including driving and driven clutch members having cooperating parts relatively movable between predetermined relative positions drivingly to connect or disconnect said clutch members, a radial projection on the driven member, means to bias the cooperating parts of said clutch members to one relative position, a chordally recessed latch pin pivotally rockable upon an axis transverse to the plane of rotation of said projection and sufficiently close to the perimeter of the orbit of the said projection to obstruct the same when the recessed side of the pin is turned to one position, a radially projecting arm fixed on said latch pin, a lever rockably secured upon a fixed axis, a drive connection between the lever and arm, and means to rock said lever with a snap action in timed relation to the movement of said carriage momentarily to rotate said latch out of projection obstructing position so as to release said driven clutch member.

23. In a motor driven business machine having a reciprocable carriage supporting a platen for rotation relative thereto and having a clutch to connect and disconnect the motor and the machine under the control of normal running circuits automatically to de-energize the

clutch and motor at a predetermined point in the cycle of the carriage, the combination comprising platen driving means rotatably to advance said platen in predetermined stages, motor driven means to drive said platen driving means including a clutch drivingly to connect said motor and platen driving means at a predetermined point in the cycle of the carriage and for a predetermined period of time, and a switch rendered operative subsequent to de-energization of the normal running circuits of the motor and clutch to continue energization of the motor for an interval long enough to drive the platen driving means through a complete cycle.

24. In a motor driven business machine having a reciprocable carriage supporting a platen for rotation relative thereto and having a clutch to connect and disconnect the motor and the machine under the control of normal running circuits automatically to de-energize the clutch and motor at a predetermined point in the cycle of the carriage, the combination comprising platen driving means rotatably to advance said platen in predetermined stages, motor driven means to drive said platen driving means including a clutch drivingly to connect said motor and platen driving means at a predetermined point in the cycle of the carriage and for a predetermined period of time, means including a switch for energizing said motor independently of the normal running circuits for the motor and clutch, and cam means driven by said clutch to render said switch means operative subsequent to the de-energization of said normal circuits and for a period controlled by said cam means.

25. In a business machine having a reciprocable carriage supporting a platen for rotary movement relative thereto, the combination comprising ratchet and pawl mechanism for rotatably advancing said platen in predetermined increments including a handle manually pivotally rockable to effect forward pivotal movement of said platen, a member coaxially arranged with respect to said handle and pivotally rockable independently thereof, driving mechanism adapted to be driven through a predetermined stroke in response to predetermined movement of the carriage, a drive connection between said driving mechanism and pivotally rockable member to rock the latter in one direction through a predetermined angle during each stroke of the driving mechanism and one way drive means between the coaxial rockable member and handle pivotally to rock the latter in synchronism with said coaxial rockable member when the latter is rocked by said driving mechanism.

26. In a motor driven business machine having a reciprocable carriage supporting a platen for rotation relative thereto, the combination comprising step by step driving means rotatably to advance said platen in predetermined increments, mechanism to actuate said step by step driving means including a rotatable shaft, means rendered operative by movement of the carriage at a predetermined point in the cycle thereof drivingly to connect the motor of said machine and said rotatable shaft for a predetermined interval thereby to rotate said shaft including means to arrest rotation of said shaft after predetermined angular movement thereof, a crank driven through one complete stroke during each cycle of the shaft, and a driving connection between said crank and said step by step driving means to advance the latter a predetermined amount during each revolution of the crank.
